MAILBOX

Frank A. Qualls, Seattle, Wash.

Application August 15, 1942; Serial No. 454,955

2 Claims. (CL. 232—17)

This invention relates to mail boxes, and particularly to mail boxes with adjustable drawers and means for retaining the drawers in position, and for the removal thereof.

In the usual construction of private mail boxes, difficulties have been found by letters becoming lodged in upper portions of the boxes and not discovered; and in damages to mails in the boxes from dust and rain, and especially difficulties, in removing the accumulated mails from the boxes, and in retaining the drawers in proper position in the boxes for receiving and storing the mails.

After carrying and delivering mails for many years, and making experiments to overcome such difficulties I have invented a box that satisfactorily meets all former objections, as hereinafter shown.

It is among the objects of this invention to provide an inexpensive and easily constructed box, and extractor drawer for receiving and removing the mail from the box, with means for retaining the drawer in closed position, and means for diverting all mail into the drawer, and for guarding against dust and water, and for easily removing such drawer and mails therewith by gravity.

A particular object is to provide such a box with an upper slot for deposit of mail and particularly letters therein, and a doorway at the lower end of the box, and a drawer slidably and rotatably disposed through the doorway, with special latching means for retaining the drawer in closed position; and means for automatically releasing from the latch by tilting and sliding the drawer for removal thereof with accumulated mails, together with a rack on top of the box for retaining newspapers and the like.

With these and other objects to be hereinafter stated, I have illustratively exemplified my invention by the accompanying drawings, of which:

Figure 1 is a perspective view of the assembled box.

Figure 2 is a perspective view of the extractor drawer.

Figure 3 is a vertical cross section view taken along the center of the box, showing the drawer in closed position, and letters therein.

Figure 4 is a similar view of the box, but showing the drawer unlatched and slightly removed, with dotted lines indicating the lowered position of the drawer and letters, when withdrawn from the box.

Like numerals on the different figures represent like parts. The box is preferably made in rectangular form, with a front wall 5, rear wall 6,

sides 7 and 8, roof 9 and floor 10. The front and rear walls are preferably extended to suitable distances above the roof to provide rack walls 5' and 6' for holding bulky packages and papers, etc. An ordinary slot 11 is provided for the deposit therein of letters, etc., with a hinged flap or cover 12 for excluding dust and rain, from the slot.

A guide plate 13 is affixed to the upper portion of the inner face of the back wall, the lower edge of which is formed with a bevel or slope inward and downward, for the purposes of a latch, and for guiding letters into the drawer below the same and to prevent letters from catching on the top of the rear wall of the drawer. The said drawer is formed with a rear wall 16, base 17 and front panel or door 18, and is slidably disposed through a doorway 19 in the lower portion of the box. The rear wall 16 is taller than the doorway, and in order to insert the drawer the base is necessarily tilted and the wall 16 then inserted and pressed back against the box wall 6. The top edge of the wall 16 is beveled with a face 15 sloping downward and inward, and so readily slides beneath the latch 14 when the drawer is inserted on an angle. When the drawer is lowered flatly upon the floor, the sloping edge 15 becomes securely locked behind the latch, and the drawer cannot then be withdrawn by a straight horizontal outward pull, and is so maintained in closed position against tampering of children, or jars of any sort, but may be readily withdrawn by a proper tilting thereof by the understanding operator.

The lower edge of the front wall 5, is also beveled to provide an inward and downward sloping face 20, the upper edge of the front of the drawer or door 18 in doorway 19, is also beveled to provide an inward and downward slope 21 which normally abuts against the face 20 when the drawer is in closed position and thus prevents entrance of dust and rain into the box and drawer from injuring the mails, indicated as letters 24. In order to prevent rain water that may run down the front wall 5 from seeping through above the door, the latter is provided with a secondary bevel 22 or face sloping downward and outward and the ridge 23 above, while normally abutting the upper face 20, tends to divert any such descending water to the outside of the door. The front face of the drawer, is preferably extended below the floor level and narrowed to provide a handle or lever 26, for tilting and operating the drawer, and for supporting the drawer with one hand by the operator while the mail is being re-

moved therefrom by the other hand, and the rear lower corner or heel of drawer base 27 is rounded which is important to facilitate the sliding or rolling of the heel along the floor of the box when the drawer is being moved into and from closed position therein, and also to facilitate the entry of the drawer over the outer edge of the floor and downward gradual movement of the drawer from outside the edge of the floor when the mail is to be removed.

In use, the drawer is inserted by tipping and lowering the rear wall 16 for passing through the doorway and the face 15 under the sloping latch 14. The drawer is then lowered upon the floor 10, and cannot be withdrawn against the latch by a horizontal pull, and the doorway will be sealed against entrance of dust and water, by the abutting bevels on the front door and lower edge of box front wall. Mail and particularly letters may be then dropped into the box slot, and will be guided between the front and rear walls of the drawer, and cannot lodge against the top or rear wall because of the sloping point 14, which also serves as the retaining latch. Any desired transparent window as 25 will enable the owner to observe when mail is in the drawer, and he may then easily withdraw the same, by tilting the lever and the drawer till the heel slides outward, and then downward over the sloping and retracted edge 10' of the floor. The mail may be then grasped in one hand and none be overlooked as the drawer has no sides for concealment. The corresponding bevels 14, 15, 20 and 21, permit the drawer to be swung open, and closed.

In the operation of removing the drawer and mail therein, it will be understood that the drawer serves as the depository, and removal of the mail is accomplished by gravity with the box, which is the guide therefor.

Both the box, and drawer are preferably made from plywood, of suitable dimensions for the several parts, and the outer surfaces of the box are covered with suitable weatherproof dressings, to prevent warping thereof, and entry of moisture therethrough.

Having described my invention, I claim as new:

1. A mail box provided with a doorway in the lower portion for removal of the mails, a drawer

slidably and rotatably disposed in the box through the doorway, a front on the drawer for a door for closing the doorway and having a bevel along the upper front edge for abutting against a corresponding bevel on the lower edge of the front wall of the box for excluding dust and water and to facilitate the tilting of the door, a plate inside the back of the box having the lower edge thereof beveled outward to guide mail into the drawer and for a latch for normally retaining the drawer in closed position against accidental and horizontal outward movement, a rear wall on the drawer higher than the doorway top and beveled backward along its top to fit beneath the beveled latch on the plate to prevent the opening of the drawer by horizontal movement, a lever extended from the door of the drawer to facilitate the tilting of the drawer, for entry and removal thereof through the doorway and for manual support of the drawer while mail is being removed therefrom.

2. A mail box provided with a horizontal passageway near the bottom thereof, a receptacle for gathering and removal of mails adjustably disposed through the passageway, said receptacle comprising a base and a front and rear wall, the top of said rear wall provided with an oblique face, a down turned guide plate affixed to the inside of the rear wall of the box for directing mail into the drawer and for a latch for extending over said oblique face of the rear wall of the receptacle for normally retaining the same in closed position, a front wall on the box having an inward sloping face, and the top of the front wall of the receptacle having a cooperating outward sloping face for abutting against the same to exclude water and dust, and to facilitate the up tilting of the receptacle for adjustment under and from said latch, said top of said receptacle front also provided with an inward and downward slope for diverting water from entering the receptacle and the rear lower corner of the receptacle base having a rounded lower rear corner to facilitate sliding movement of such corner along the floor of the box, and to permit the receptacle to be gradually inserted over the front edge of the floor and also removed therefrom when mail is to be removed therefrom.
